CLAIM

The ornamental design for a smoking accessory, as shown and described.

DESCRIPTION

FIG. 1 is a perspective view of the front, top, and left side of a smoking accessory showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top elevational view thereof;
FIG. 7 is a bottom elevational view thereof;
FIG. 8 is a perspective view of the front, top, and left side of the smoking accessory in a second embodiment;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top elevational view thereof; and,
FIG. 14 is a bottom elevational view thereof.

1 Claim, 6 Drawing Sheets
